MYER SIEGEL, OF NEW YORK, N. Y., ASSIGNOR OF ONE-HALF TO CHARLES SIEGEL, OF NEW YORK, N. Y.

DISHWASHER

Application filed August 13, 1932. Serial No. 628,739.

This invention relates to dish washing devices and particularly to an improved dish washer which is to be used by hand, the object being to provide an improved and simplified structure which may be readily brought into contact with the dishes during the washing action to secure a quick washing without the necessity of placing the hands in the dish water.

10 Another object of the invention is to provide an improved dish washer wherein a washing head is used in connection with a continuous or intermittent supply of water, the structure being so formed that it may be 15 moved by hand over the dish being washed.

A further object of the invention is to provide a dish washer utilizing a washing head consisting of bristles or other rubbing members in connection with a supply of water directed on and within the head, so that as the head is rubbed or moved over the dish or other 20 object, water is supplied to the dish or other object.

An additional object, more specifically, is to 25 provide a dish washer utilizing either a continuous or an intermittent supply of water, and means for intermittently providing a supply of liquid soap.

In the accompanying drawing—
30 Figure 1 is a top plan view of a dish washer disclosing an embodiment of the invention;

Figure 2 is a sectional view through Figure 1 approximately on line 2—2;

Figure 3 is a transverse sectional view 35 through Figure 2 on line 3—3;

Figure 4 is a view similar to Figure 1 with a portion broken away, the view disclosing a modified construction to that illustrated in Figure 1;

40 Referring to the accompanying drawing by numerals, 1 indicates what may be called a handle or support, the same being provided with a thumb-receiving member or loop 2, and with an enlarged apertured head 3. A 45 lever 4 is pivotally mounted at 5 on the handle 1, said lever having at one end a rack 6 and at the other a finger-receiving loop 7. The rack 6 is adapted to be continually in mesh with the gear wheel 8 whereby when 50 the lever 4 is swung back and forth on its

pivot with respect to the handle 1, the gear wheel 8 will be rotated back and forth.

As shown in Figure 2, the gear wheel 8 is soldered or otherwise rigidly secured to the upper end of a tube 9, which tube is provided with an inturned flange 10 so that the shoulder 11 of the sleeve 12 may rest against the same. A ring or abutment 13 is clamped to the reduced extension 14 of sleeve 12 by a suitable set screw 15. A flexible hose 16 has one end fitted over the reduced extension 14 so that water or other liquid passing through the hose 16 will be discharged through the sleeve 12 into the tube 9. When the device is in use, the hose 16 may be of any desired length and is connected to a continuous supply of water, as, for instance, the ordinary faucet found adjacent a kitchen sink.

Beneath the enlargement 3 a ring or abutment 17 is provided, said ring being clamped in position by a suitable set screw 18. It will thus be seen that the tube 9 may easily rotate with the gear wheel 8 but cannot move longitudinally through the enlargement 3. At the lower end tube 9 is provided with an internally threaded portion 19 which receives the threaded extension 20 of the cleaning head 21. This cleaning head is shown as being provided with bristles 22, but if desired it could be provided with other cleaning members, as, for instance, a piece of cloth. A bore 23 extends from the upper end of the head downwardly and is reduced at 24 so that the central bore 25 is smaller than the bore 23, while at the point 24 a number of passageways 26 converge, said passageways extending downwardly at such an angle that water passing therethrough will strike the outer surface of the bristles 22 so as to wash objects therefrom.

When the device is in operation, the flexible tube or hose 16 is connected to a continuous water supply, as above mentioned, and the handle 1 and lever 4 are grasped by placing the thumb through the loop 2 and placing certain of the fingers through loop 7. The device is then moved until the bristles 22 come in contact with a dish or other object to be washed. As the water continues to flow, the bristles may be rubbed against the

100

dish so as to clean the same. In addition, by moving the lever 4 back and forth the cleaning head 21 may be rotated in addition to being moved back and forth over the dish. 5 In this way both a back and forth and a rotary movement is given to the cleaning head. While this is being done the water is continually flowing, and while the cleaning head loosens any dirt or other objects from the 10 dish, the water will wash the same away. Ordinarily the rotary movement given to the tube 9 is slightly less than one complete revolution, but if desired it can be made more than one revolution by varying the relative 15 sizes of the rack 6 and the gear wheel 8.

In Figure 4 a slightly modified form of the invention is shown wherein means have been provided for causing the tube 9 to rotate a great number of times upon each actuation of the lever 4. Most of the structure 20 shown in Figure 4 is identical with that shown in Figure 1, so that only the modified parts will be given additional numbers. As shown in this figure, the rack 6 meshes with 25 the gear wheel 8' which is rigidly secured to a large gear wheel 27, which gear wheel continually meshes with the gear wheel 8. The gear wheels 8' and 27 are rotatably mounted on the handle 1 by a suitable journal pin 30 28 and functions to multiply the number of revolutions of the tube 9 as the lever 4 moves back and forth.

What is claimed is:

35 A dish washer including a cleaning head, a tubular member carrying said head, said tubular member at the upper end being provided with a turned-in flange, a sleeve having a shoulder, said sleeve being rotatably positioned in said tubular member with the shoulder resting against said flange, said sleeve having a tubular extension for the reception 40 of liquid which is discharged through the sleeve and the tubular member on to said head, a gear wheel rigidly secured to said tubular member, a handle having an apertured portion through which the portion of 45 the tubular member below the gear wheel extends, an abutment rigidly secured to said tubular member immediately below said handle, a rack continually meshing with said gear wheel, a lever pivotally mounted on said handle and rigidly connected with said rack, whereby when said lever is actuated said gear wheel will be rotated for rotating the tubular member and said head. 50 55
